UNITED STATES PATENT OFFICE.

JAMES McDONOUGH, OF MONTCLAIR, NEW JERSEY.

HORSESHOE-CALK.

1,204,043.

Specification of Letters Patent.

Patented Nov. 7, 1916.

Application filed July 17, 1916. Serial No. 109,666.

To all whom it may concern:

Be it known that I, JAMES McDONOUGH, a citizen of the United States, and a resident of Montclair, in the county of Essex and 5 State of New Jersey, have invented a new and Improved Horseshoe-Calk, of which the following is a full, clear, and exact description.

My invention is an improvement in that 10 class of calks whose tangs or shanks are provided with lateral ribs.

The improvement is embodied in the novel construction and combination of parts hereinafter described.

15 In the accompanying drawing:—Figure 1 is a bottom plan view of a horseshoe illustrating my invention; Fig. 2 is a perspective view of one of the calks as they are to be placed upon the market separate from the 20 shoe; Fig. 3 is a vertical transverse section on the line 3—3 of Fig. 1, showing the new form of calk driven into place; Fig. 4 is a finished view of the same after the calk is 25 secured; and Fig. 5 is a detail perspective view of a modified form of toe calk.

In my extensive experience in this art, I have discovered it is a great advantage to the horse to have more than three calks on each shoe, and therefore I prefer to apply 30 one calk on each side of the shoe in addition to those on the heel and toe. Thus I apply calk 16, as shown in Fig. 1, the same hav-

ing its inner side provided with a flat tapered tang 15, and with wedge-shaped fins 17, which project laterally in opposite directions from the base of the tang. The side grooves 11 of the shoe are provided with holes 12. When the calk is applied, as shown in Figs. 1 and 3, the tang enters the hole 12, and the wedge-shaped fins or ribs 17 35 enter adjacent portions of the groove 11 and their alined outer edges rest on the bottom of the groove, so that the calk is very firmly seated and prevented from turning or twisting. 40

45 In the operation of attaching the calk, it is not necessary that the same shall be heated, in order to upset or rivet down the free end of the tang. In Fig. 5 I show a toe calk 16' having a cylindrical tang 15', 50 whose base is constructed with lateral tapered fins 17'. This calk is shown applied in Fig. 1.

I claim:

The combination with a horseshoe having 55 a longitudinal side groove in its face, and nail holes therein, of a calk having its inner side or face provided with a tapered tang for insertion in one of said holes and lateral wedge-shaped fins formed at the base of the 60 tang and on opposite sides of the same, the fins being adapted to seat in the groove in the manner described.

JAMES McDONOUGH.
